UNITED STATES PATENT OFFICE.

LEE C. STEELE, OF PLYMOUTH, AND ROSCOE STEELE, OF NORTH MANCHESTER,
INDIANA.

WIRE-BOUND BOX.

1,123,416.

Specification of Letters Patent.

Patented Jan. 5, 1915.

Application filed April 5, 1913. Serial No. 759,214.

To all whom it may concern:

Be it known that we, LEE C. STEELE and ROSCOE STEELE, citizens of the United States, residing, respectively, at Plymouth and North Manchester, in the respective counties of Marshall and Wabash and State of Indiana, have invented certain new and useful Improvements in Wire-Bound Boxes, of which the following is a specification.

10 The invention relates generally to an improvement in boxes of the wire bound type, and particularly to a reinforcing means designed for independent application to the sides, bottom, and top of the box, which 15 means are constructed to present a relative endwise bearing, and to interlock, when the parts are assembled in box forming relation, thereby preventing relative endwise movement or lateral twisting of the sections.

20 The main object of the present invention is the provision of a specific form of cleat, designed to be secured to the sides, bottom, and top of the box, and disposed in relatively reverse positions on the top and bottom 25 with respect to their positions on the sides, each of said cleats having beveled ends, and including a relatively narrow rib, whereby in the box forming relation of the sections the beveled ends of the cleats will 30 interfit for endwise bearing, and the ribs will interlock to prevent twisting of the sections.

The invention in its preferred form of details will be described in the following 35 specification, reference being had particularly to the accompanying drawings, in which:—

Figure 1 is a perspective view illustrating the improved construction. Fig. 2 is a perspective view of the improved reinforcing cleat.

Referring particularly to the accompanying drawings, the improved box, in the preferred mode of construction, comprises the usual shook including the bottom 1 and sides 2 of the box, connected in assembled and hinged disposition by the usual binding wires 3 secured in position by staples 4. The top 5 corresponds to the bottom 1 and 45 is provided on its upper surface with tie wires 6, secured thereto in any suitable manner, the ends of the tie wires being inter-twisted to form eyes 8, for a purpose which 50 will later appear.

55 The above described construction is the

usual one in this type of box, and it is to be understood that by such description, and by the illustration thereof, we intend to designate any type of box constructed to which the improved reinforcing cleat may 60 be applied.

The salient feature of the present invention resides in a reinforcing cleat, designed to be duplicated in required number, and applied to the sides, bottom, and top of the 65 box, the cleats being constructed and arranged for interfitting and interlocking.

The improved cleat, which is illustrated more particularly in Fig. 2 of the drawings, comprises a strip of suitable material, preferably wood, having what may be termed its relatively outer edge 9 coextensive in length with the width of the particular section of the box with which it is designed to co-operate. The strip is of sufficient thickness to 75 provide the necessary strength, and the respective ends thereof are beveled at 10, on a 45° angle. The relatively inner edge 11 of the strip is provided with a rib or tongue 12 of approximately one-half the width or 80 thickness of the strip. One side edge of the tongue is coincident with one side edge of the strip, constituting what will be herein-after termed the plain edge of the strip, the reduced width of the tongue as compared 85 with that of the strip, forming a shoulder 13 on the opposite side of the strip.

The cleats are secured to the respective ends of the sides, bottom, and top, and are arranged in reversely disposed pairs on such 90 parts. That is to say, the cleats will be secured to the sides of the box with their plain edges approximately alined with the end edges of such sides, while the cleats as secured to the top and bottom are arranged 95 with their plain edges inwardly, or their shouldered edges in alinement with the end edges of the top and bottom. As thus secured, in folding the sections of the shook into box forming relation, it will be noted 100 that the beveled ends 10 of the respective cleats on the sides and bottom will bear squarely against one another, while the tongue 12 of the bottom cleat will interlock in rear of the tongues 12 of the side cleats. The ends 14 of the box are secured in place 105 by arranging said ends in contact with the surfaces of the cleats remote from the end edges of the sides and bottom, the cleats forming a substantial portion against which 110

the ends will accurately fit and to which they may be nailed or otherwise secured. The top, when applied in the usual manner, will rest in such position that the beveled 5 ends of the top cleats will bear squarely against the beveled upper ends of the side cleats, while the ribs 12 of the top cleats will interfit in rear of the ribs or tongues 12 of the side cleats, as will be plain from Fig. 1 10 of the drawings. The top is secured in place by passing the projecting ends 15 of the terminals of the wires 3 through the eyes 8 of the top tie wire, and securing said terminals in any appropriate manner. As thus 15 constructed, it will be understood that the end of the box is provided with top, bottom and side cleats having their meeting ends snugly and squarely interfitting and having their projecting ribs or tongues interlock- 20 ing, it being understood that the width of the tongue is approximately one-half the similar dimension of the maximum width of the cleat, whereby the interfitting tongues snugly fit, being braced against in- 25 ward movement by the end walls of the box.

What is claimed is:—

1. A box including sides, top, bottom and ends, cleats secured to the sides, top and bottom having beveled ends and a longitudinal flange terminating beyond the plane of the beveled ends, the cleats being disposed in 30 alternating positions whereby the beveled ends will abut and the ends of the flanges

will overlap in interlocking relation, and means for securing the ends to the cleats. 35

2. A box including sides, top, bottom and ends, cleats secured to the sides, top and bottom having beveled ends and a longitudinal flange flush with one side of the cleat and extending beyond the plane of the beveled 40 ends, the cleats being disposed in alternating relation whereby the beveled ends will abut and the ends of the flanges will overlap in interlocking relation, and means for securing the ends to the cleats. 45

3. A box including sides, top, bottom and ends, cleats secured to the sides, top and bottom having beveled ends and a longitudinal flange flush with one side of the cleat and extending beyond the plane of the beveled 50 ends, the flange ends being at right angle with relation to the base of the cleat, the cleats being disposed in alternating relation, whereby the beveled ends will abut and the ends of the flanges will overlap in interlocking relation and abut squarely against the inner edges of the adjoining cleats, and means for securing the ends to the cleats. 55

In testimony whereof we affix our signatures in presence of two witnesses.

LEE C. STEELE.
ROSCOE STEELE.
